UNITED STATES PATENT OFFICE.

HENRY J. HEINZ, OF PITTSBURG, PENNSYLVANIA.

DESIGN FOR A WATCH-CHARM.

SPECIFICATION forming part of Design No. 22,321, dated April 4, 1893.

Application filed December 1, 1892. Serial No. 453,780. Term of patent 7 years.

To all whom it may concern:

Be it known that I, HENRY J. HEINZ, of Pittsburgh, in the county of Allegheny and State of Pennsylvania, have invented a new and original Design for Watch-Charms, of which the following is a full, clear, and exact description, reference being had to the accompanying drawing, which shows in side elevation a watch-charm embodying my design.

My design consists in a watch-charm, having an oblong body somewhat tapering, in configuration resembling that of a cucumber, with surface warts, a stem, and with surface

In the drawing, 2 represents the watch- 15 charm of oblong somewhat tapering form, having at one end a stem-like projection 3, and surface letters formed thereon in intaglio or relief.

I claim—

The design for watch-charms substantially as herein shown and described.

In testimony whereof I have hereunto set my hand.

HENRY J. HEINZ.
